Edward R. Leigh, INVENTOR:
BY
Meader Henry Fairbanks, ATTORNEYS.

UNITED STATES PATENT OFFICE.

EDWARD R. LEIGH, OF PHILADELPHIA, PENNSYLVANIA, ASSIGNOR OF ONE-HALF TO
EDWARD W. DUGDALE, OF KEARNEY, NEW JERSEY.

FLOOR-LEVEL STOP FOR ELECTRICALLY-OPERATED ELEVATORS.

Application filed September 22, 1917. Serial No. 192,649.

To all whom it may concern:

Be it known that I, EDWARD R. LEIGH, a citizen of the United States, residing in the city and county of Philadelphia, State of Pennsylvania, have invented a new and useful Floor-Level Stop for Electrically-Operated Elevators, of which the following is a specification.

My present invention relates to electrically operated elevators, and in its broad and generic scope, consists of novel means for automatically bringing the elevator car to the floor level when the car stops a slight distance above or below the level of the floor.

It further consists of a novel arrangement of electric circuits which are open when the car is running but which are closed when the controlling switch is in its neutral position and the car stops a predetermined distance above or below the level of the floor.

Other novel features of construction and advantage will hereinafter more clearly appear in the detailed description of my invention.

For the purpose of illustrating my invention, I have shown in the accompanying drawings a typical embodiment of it which is at present preferred by me, since this embodiment will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents, in sectional elevation, a floor level stop for electrically operated elevators embodying my invention, the section being taken on line 1—1 of Figure 2.

Figure 2 represents a section on line 2—2 of Figure 1.

Figures 3, 4 and 5 represent diagrammatically wiring diagrams of my invention.

Figure 6 represents a front elevation of a contact carrying plate and its adjuncts and a portion of the elevator car.

Figure 7 represents a section on line 7—7 of Figure 2 and showing in dotted lines the position certain of the contacts assume when the car stops above or below the floor level.

Figure 8 represents a diagrammatical view of the motor and control circuits.

Similar numerals of reference indicate corresponding parts.

Referring to the drawings:

1 designates the car of an electrically operated elevator and 2 designates the wall of the shaft in which the car operates. 3 designates the floor level. 4 designates the controller switch which is provided with an actuating handle 5 mounted on a shaft 6. 6 7 designates a link fixed to the shaft 6 and pivotally connected to a rod 8 which at its other end is pivotally connected to a bell crank lever 9 which is fulcrumed at 10 to a keyway 11.

12 designates a link pivotally connected to one end of the bell crank 9 and with a plate 13 carried by a key 14 slidably in the keyway 11, which is fixed to the top of the car 1 in any desired manner. The plate 13 75 has secured thereto in any desired manner a contact carrying plate 15 of insulating material in which are mounted the binding posts 16, 17, 18 and 19 which extend through the contact carrying plate 15 and are adapted to be moved into a position to contact with a wall contact plate 20 which is secured in any desired manner with respect to the wall of the elevator shaft. This wall contact plate preferably has its upper and lower 85 portions inwardly curved. The bell crank lever 9 is preferably provided with a tension device 21 which, as seen in Figure 1, consists of a spring, one end of which is connected to an arm of the bell crank lever 90 and the other end of which is connected to the key way 11.

22, 23, 24 and 25 designate lead and return lines of the electric circuit which are connected with the switch and with the source of electric energy which operates the elevator car, these conductors passing through the trailer cable 26. The line 22 extends to the switch contacts 27 and 28. The line 23 extends to the switch contacts 29 and 30. The line 24 extends to the switch contact 31 and the line 25 extends to the switch contact 32. The controller handle 5 is provided with a fan-shaped hand 33 which forms a selector.

34 designates a line leading from the line 22 to the wall contact plate 20. 35 designates a line leading from the line 25 to the

binding post 16. 36 designates a line leading from the line 23 to the binding posts 17 and 18. 37 designates a line leading from the line 24 to the binding post 19. 5 When the grasping portion of the controller switch is in the position seen in Figure 3, the current passes through the circuit, see Fig. 8, to cause the elevator car to travel downwardly. When the selector 33 is in 10 contact with the contacts 29 and 31 of the switch, the current passes through the circuit to cause the elevator car to travel upwardly. When the controller handle is in the running position, the rod 8 will be 15 drawn downwardly, thereby causing the contact carrying plate 15 to be moved out of the path of the wall contact plate 20. When, however, the controller handle of the switch is in its neutral position, as seen in 20 Figures 1, 4 and 5, the contact carrying plate 15 is moved into the path of the wall contact plate 20.

Assuming now that the car should stop above the floor level, the contacts of the 25 binding posts 19 and 18 will close the circuit through the wall contact plate 20 and the current will pass through the lines 23 and 36 to the binding post 18 and through the lines 24 and 37 to the binding post 19, thence 30 through the wall contact plate 20 and line 34 to the line 22. Assuming that the car stops below the floor level, then the contacts of the lower binding posts 16 and 17 will 35 close the circuit through the wall contact plate 20, and the current will pass through the lines 25 and 35 and the lines 23 and 36 to the contacts of the binding posts 16 and 17 respectively and thence through the wall contact plate 20 and line 34 to the line 22, 40 thus causing the car to move upwardly until it is flush with the floor level.

If the elevator stops above the floor level contacts 16 and 17 come into contact with the cam 20 which gives the same result as 45 if the operating handle 5 were in "down" position and current comes from the line through the car switch, reversing the magnets.

Current comes from the line 38, see Figure 50 8 of the drawings, to line 22, thence to the contacts 27 and 28 of the car switch. The current also passes through line 34 to the cam 20 through contacts 16 and 17 and lines 55 35 and 36. Line 36 leads by way of rod 23 to the potential switch and causes such potential switch to close. When the potential switch closes, the current is then allowed to pass from the contact 41 to contact 42, and from contact 43 to contact 44, thence to one 60 side of the reversing magnets. Line 35 leads to the down magnet by way of line 25 causing the down magnet to close, thus allowing current to pass from contacts 42 to contacts 45, thence by way of line 46 to the 65 motor at 47.

Current also passes from contact 44 through contact 48, thence by way of line 49 to the motor at 50, current being returned to the line from 51 by way of line 39, thus applying the current and allowing the 70 motor to rotate and move the elevator in its down direction.

If the elevator stops below the floor level, contacts 19 and 18 come into contact with cam 20 giving the same results as if the operating handle 5 were in an "up" direction. 75 Current comes from the line through the car switch reversing the magnets as follows:

The current comes from line 38 to line 32 thence to contacts 27 and 28 to the car switch. Current also passes from line 34 to the cam 20 through contacts 19 and 18 and lines 37 and 36. The action of the current by way of line 36 to the potential switch is 80 the same as already described with reference to the down direction.

The line 37 leads to the up magnet by way of line 24 causing the up magnet to close and allowing current to pass from contacts 42 to 48 thence by way of line 49 to the 90 motor at 50, and then also allows current to pass from contacts 44 to contacts 45, thence by way of line 46 to the motor at 47, the current being returned to the line by line 39, thus completing the circuit and allowing the motor to rotate and move the elevator in an up direction. 95

It will be understood from the foregoing that in accordance with my present invention, I have devised, electrically controlled means to automatically bring the elevator car to the floor level if it should stop above or below such level, it being understood that the wall contact plate 20 may have any desired length. The contact carrying plate 100 15 is mechanically positioned in the path of the wall contact plate 20 when the controller handle is in its neutral or inoperative position.

It will now be apparent that I have devised a novel and useful floor level stop for electrically operated elevators, which embodies the features of advantage enumerated as desirable in the statement of the invention and the above description, and while I 110 have, in the present instance, shown and described a typical embodiment of it which will give in practice satisfactory and reliable results, it is to be understood that this embodiment is susceptible of modification in 115 various particulars without departing from the spirit or scope of the invention or sacrificing any of its advantages.

It will be seen that when the car stops a given distance above the floor level, the contacts 16 and 17 come into contact with the wall plate 20, and if the car stops below the floor level, the contacts 18 and 19 come into contact with the plate 20, and the circuit is 120 closed the same as would occur by movement 125 130

of the car switch, since line 34 is a continuation of line 22, line 35 of line 25, line 36 of line 23, and line 37 of line 24. Contacts 16 and 17 engaging the wall plate 20 have the same result as if the selector is in its down position, closing the circuit between contacts 28, 30 and 32. If the circuit is closed through contacts 18 and 19, the same result is obtained as if the handle were in its up position and closing the circuits between contacts 27, 29 and 31.

Having thus described my invention, what I claim as new and desire to secure by Letters Patent, is:—

15 1. In a device of the character stated, the combination with the elevator car, of electrically controlled means to automatically bring the car to the floor level whether it over-runs or under-runs such floor level, 20 said means including a stationary contact for each floor level and a plurality of co-operating contacts carried by the car.

2. In a device of the character stated, the combination with the elevator car, of a control switch, and means electrically controlled when said switch is in neutral position to automatically bring the car to the floor level whether it over-runs or under-runs such floor level, said means including 30 a stationary contact for each floor level and a plurality of co-operating contacts carried by the car.

3. In a device of the character stated, the combination with the elevator car, of an electric circuit including a controlling switch to effect the actuation of said car, and an auxiliary circuit automatically controlled when said switch is in neutral position to return the car to the floor level 40 whether it over-runs or under-runs such floor level, said auxiliary circuit including a stationary contact for a floor level and a plurality of co-operating contacts carried by the car.

45 4. In a device of the character stated, the combination with the elevator car, of an electric circuit controlling the movement of said car and including a manually actuated switch, and an auxiliary circuit automatically controlled when said switch is in neutral position to automatically bring the car to the floor level whether it over-runs or under-runs such floor level, said auxiliary circuit including a stationary contact for a 50 floor level and a plurality of co-operating contacts carried by the car.

5. In a device of the character stated, the

combination with the elevator car, of an electric circuit to effect the operation of said car and including a switch, auxiliary circuits including a stationary contact for a 60 floor level and movable contacts carried by the car, said stationary contact being in the path of the movable contacts, and means actuated by said switch to render the movable contacts of the auxiliary circuits inoperative when the switch is in running position and operative whether the car over-runs or under-runs the floor level, when the switch is in neutral position.

6. In a device of the character stated, the combination with the elevator car, of an electric circuit to control the travel of the car and including a switch, electrically controlled means to automatically bring the car to the floor level whether it over-runs or 75 under-runs such floor level, said means including a stationary contact, and contacts supported to move in unison with the car and to co-operate with said stationary contact, and means controlled by said switch 80 to render said electrically controlled means operative or inoperative.

7. In a device of the character stated, the combination with the elevator car and its shaft, of a wall contact plate carried by said shaft, an electric circuit to effect the raising and lowering of said car and including a manually controlled switch, a movable contact carrying member actuated by said switch to bring it into operative or inoperative position with respect to said wall contact plate carried in said shaft, contacts carried by said member and included with said wall contact plate in an auxiliary circuit controlled by said switch whether the 95 car over-runs or under-runs the floor level.

8. In a device of the character stated, the combination with the elevator car, of a contact carrying plate movably carried by said car, an electric circuit including contacts 100 mounted on said plate and including a stationary contact, electric circuits to effect the raising and lowering of said car and including a manually controlled switch, and connections from said switch to said contact 105 carrying plate to move the contacts carried by said plate into the path of said stationary contact.
